Nicholas Equipment Company, a partnership

Application September 29, 1945, Serial No. 619,367

11 Claims. (Cl. 51—85)

1

This invention relates to an improved polishing or abrading machine, and especially to an improved machine which will be particularly well adapted for polishing knife blades or similar articles. These, therefore, are the general objects of the present invention.

A more specific object of the invention is the provision of an improved actuating mechanism for passing workpieces between a pair of coacting polishing or abrading rolls, as well as the provision of an improved mechanism for controlling the number of passes to be made by the workpieces.

Another object of this invention is to provide a mechanism for polishing or abrading work pieces, between a pair of coacting polishing or abrading rolls, including a method of control for the peripheral speed of the rolls, regardless of variations between the rolls caused by wear and the like.

A further object of the invention is to provide an improved polishing or abrading machine, of the type using a pair of coacting rolls between which the work is passed, the mechanism of which will be so arranged as to eliminate, for practical purposes, undesired vibrations and chattering, either of which is apt to blemish the work pieces, as well as result in early deterioration of the mechanism.

Other objects and advantages of this invention will become more apparent from the following specification, reference being had to an embodiment of the invention illustrated in the accompanying drawings. The essential features of the invention will be summarized in the claims.

In the drawings, Fig. 1 is a front elevation of an abrading or polishing machine constructed in accord with the present invention; Fig. 2 is an end elevation of the machine, certain parts being broken away to more clearly illustrate the internal construction; Fig. 3 is a horizontal section through the machine, the plane of the section being illustrated by the offset lines 3—3 of Fig. 1; Fig. 4 is a sectional detail of a portion of the mechanism used to control the position of the abrading rolls, the plane of the section being indicated by the lines 4—4 of Fig. 1; Fig. 5 is a diagram of the mechanism used to pass the workpieces between the polishing or abrading rolls, and Fig. 6 is a diagram of electrical circuits used to control the operation of the roll driving motors.

In general, the machine illustrated in the drawings comprises a substantially rectangular frame-like structure 10, provided with a table 11. A pair of polishing rolls 12 and 14 are supported with their axes parallel with each other in a horizontal plane beneath the table 11 and within the frame structure 10. These rolls are driven at a relatively high rate of speed prefer-

2

ably by respective combined motor and speed reduction units 15 and 16 which are mounted on the table 11. These units are of a type to facilitate a comparatively fine and individual adjustment of the peripheral speed of their respective rolls.

Workpieces "A," supported by a workholder 17, are reciprocated up and down between the rolls by a hydraulically actuated mechanism mounted within a hollow column 18 which rises vertically from substantially the center of the table 11. A mechanism driven by a motor 100 atop the table 11 imparts a substantially horizontal movement to the workpieces as they pass between the rolls 12 and 14. The speed of travel of the workpieces is controlled by a pair of settable knobs 20 and 21 which are carried by an instrument panel 22 at the front of the machine, while the number of passes the workpieces are to make is controlled by a manually operable knob 23 also positioned on the instrument panel.

A feature of the present invention is the method of and mechanism for controlling the peripheral speed of the abrading rolls 12 and 14. A pair of ammeters 24 and 25 are mounted on the instrument panel and are so connected in the electrical circuit of the machine that the operator may accurately determine when the peripheral speed of the abrading rolls has been equalized. I have found that the peripheral speed is synchronized when the current flowing through each motor is identical. Suitable handwheels 26 and 27 mounted on respective speed-reduction units 15 and 16 permit manual adjustment of the peripheral speed of their respective rolls.

The frame 10 comprises, as shown in Figs. 1 and 2, a rectangular base 30 having corner posts 31 in the form of angle irons. These posts support the table structure 11. Suitable cross braces, some of which are shown in Fig. 2, at 32, serve to give rigidity to the frame structure. The table 11 has a downwardly extending skirt 33 from which pivoted hangers 34 depend. The rolls 12 and 14 are each mounted between the lower ends of these hangers.

The rolls illustrated are polishing rolls. These rolls are indicated as being built up of a series of fabric discs which are assembled on shafts 35 and which are held thereon by clamping discs 36 and nuts 37. The fabric discs are yieldable and generally have their peripheries impregnated with a polishing rouge, emery or the like, dependent upon the type of polishing or abrading operation to be performed.

The rolls 12 and 14 are journaled in the lower ends of the hangers 34 with their axes parallel with each other in substantially the same horizontal plane, and with their bite at the transverse center of the frame. As shown, the ends of each roll shaft are mounted in self-aligning bear-

ings 38 which in turn are adjustably positioned in the lower ends of their respective hangers 34 by screws 39. Suitable collars 40 prevent axial displacement of the shafts in their bearings.

The upper ends of the roll supporting hangers 34 are pivoted as at 41 to the table 11 and are swingable about their pivots to enable the rolls to be moved toward and from each other and thereby adjust their bite. The movement of the hangers is controlled by hand wheels 42 (Figs. 1 and 4). Each hanger is provided with a threaded rod 43. These rods are pivoted as at 44 to the respective hangers and extend outwardly therefrom toward the sides of the frame 10 where they are embraced by threaded sleeves 45. The sleeves 45 for respective rolls are journalled in respective beams 46 (Figs. 3 and 4) the ends of which are pivoted as at 47 in the frame posts 31. Hand wheels 42 are secured to the forwardly facing sleeves 45 which are connected by gears 48 and drive chains 49, with the respective rearwardly facing sleeves 45. Each sleeve 45 is prevented from axial movement by an arm 79 carried by a beam 46 and arranged to coact with a slot 50 in its sleeve. Accordingly, if either hand wheel 42 is rotated, its respective roll 12 or 14 will be moved toward or from the other roll, the axes of the rolls remaining parallel at all times. This provides an accurate adjustment of the pressure between the rolls as well as providing for accurate alignment of the roll bite with the workpieces.

The combined motor and speed reduction units 15 and 16 are best illustrated in Fig. 3. These units are substantially identical, each comprising an electric motor 51, the armature shaft 52 of which extends into a housing 53 of a speed reducer unit. Secured to the shaft 52 is a cone 54 to the hub 55 of which a cooperating cone 56 is splined. The cone 56 is moved to and from the cone 54 by a nut 57 which is restrained from rotation by the housing and which has a lug 58 in engagement with a peripheral groove 59 in the hub of the cone. The nut is moved axially by a threaded shaft 60 to which one of the hand wheels 26 or 27 is secured.

A V shaped belt 61 connects the variable pitch cones 54, 56 with a similar pair of cones 62, 63, which actuate the driven shaft 64 of the speed reducer unit. The cone 62 is splined to shaft 64 and has an elongated hub 65 to which the cone 63 is splined. A compression spring 66 is interposed between the cone 63 and a collar 67 on the hub of the cone 62 and serves to move the cones 62, 63 toward each other to eliminate the slack in the belt 61. The construction is such that as the cones 54, 56 are separated, the cones 62, 63 approach each other, thus varying the relative speeds of the shafts 52 and 64 in the usual manner. The speed reducer shafts 64 are each provided with sheaves 68 which are drivingly connected with sheaves 69 on their respective roll shafts 35 by driving belts 70, as indicated in Fig. 2.

The workholder 17 is best illustrated in Figs. 1 and 2 and as there shown it comprises a plate 71 to which the workpieces "A" are clamped in any suitable manner. The upper end of the plate 71 is secured to a T rail 72 which is mounted between a pair of inverted T rails 73 carried by a carriage 74. Preferably, the arrangement is such that the workholder may be slid into position on the carriage. The carriage is pivotally connected by a pair of parallel links 77 and 78 to outwardly extending arms 75 of a sleeve 76, which is slidably mounted on the column 18.

The sleeve 76 is reciprocated on the column 18

by a hydraulically operated mechanism to thereby pass the work "W" vertically between the rolls 12 and 14. Mounted in the frame 10 (Figs. 2 and 5) is an oil storage tank 80 from which oil is drawn through a conduit 81 by a pressure pump 82. This pump is actuated by an electric motor 83. The fluid passes from the pump 82 through a conduit 84 to a reversing valve 85. In the position of the valve 85 shown in Fig. 5, the fluid under pressure passes from the valve through a conduit 86, a regulating valve 87, and a conduit 88 to the lower end of a cylinder 89, thus raising the piston 90 thereof. The cylinder 89 is positioned within and is secured to the column 18, while the upper end 15 of the piston rod 91 thereof is secured to a bar 92 (Fig. 2) by nuts 93. This bar extends outwardly from the column 18 through slots 94 therein and its outer ends are secured to the sleeve 76.

While the piston and workholder move upwardly, fluid is discharged from the upper portion of the cylinder 89 through a conduit 95, a regulating valve 96, and a conduit 97 to the reversing valve 85, from which the fluid returns through a discharge or exhaust conduit 98 to the storage tank 80. The reversing of the control member or piston 90 of the reversing valve 85 causes the reversal of the direction of fluid flow above described between the reversing valve 85 and the cylinder 89 and accordingly lowers the sleeve 76 and workholder 17.

As heretofore mentioned, the workpieces are moved horizontally while they pass between the rolls 12 and 14. The mechanism for accomplishing this is best shown in Fig. 3. A motor 101 is mounted on the table 11 and is provided with a speed reducer unit indicated at 101. The driven shaft 106 of the unit 101 is provided with an eccentric pin 102 which is connected by a link 103 with a slide 104. This slide is mounted in a guide-way 105 carried by the table 11 and embraces the parallel link 77 heretofore described as connecting the sleeve 76 with the workholder 17. This rotation of the shaft 106 causes the workholder to be reciprocated axially of the polishing rolls. The amount of this axial movement is small and its frequency great in comparison with the vertical movement. Thus an even polishing action is accomplished.

The frequency of the horizontal travel of the workholder is determined by the rate of speed of the speed reducer shaft 106. The rate of speed and accordingly the frequency of the vertical movement is determined by the regulating valves 87 and 96. These valves are identical in construction and are diagrammatically illustrated in Fig. 5. Fluid under pressure flows from the reversing valve 85 into one of these valves, it enters the lower chamber 110 of the valve and forces a valve member 108 from its seat against the action of a spring 109. Thereupon the fluid passes, substantially without restriction, into the upper chamber 110 of the valve and thence to one end of the cylinder 89. However, the discharging fluid from the other end of the cylinder 89 passes directly into the upper chamber 110 of the other regulating valve 96. The valve member 108 of this valve is closed due to the action of its spring 109 and the absence of pressure in its lower chamber, accordingly this returning fluid must pass through a restricted orifice 111 in the wall between the upper and lower chambers. The effective area of the orifice 111 is regulated by an adjustable needle valve 112 to which the respective speed control knob 20 or 21 is secured. The controlling of the rate of travel of the

workholder by controlling the flow of fluid from the cylinder 89 provides an accurate regulation of the rate of travel and is independent of pulsating effects of the pump. Likewise, as pressure is maintained at both ends of the piston, the movement of the workholder is steady and even, thus enhancing the polishing operation. The elimination of gear or cam driven mechanism for passing the work between the polishing rolls assists materially in reducing vibration and chattering of the workpieces. The use of a hydraulic drive system permits infinite variations in the rate of travel of the workpieces and permits adjustments to be made for the purpose of eliminating vibratory effects which are ordinarily present in machines of this general type.

The length of vertical stroke imparted to the workholder is controlled by a pilot valve 114. This valve in turn controls the reversing valve 85 and is best illustrated in Fig. 5. The pilot valve may comprise a cylinder provided with ports 115 and 116 which are connected to opposite ends of the reversing valve 85 by conduits 117 and 118. The pilot valve is also provided with two other ports 119 and 120 which are connected by conduits 121 and 122 with the pressure line 84 and exhaust line 98 of the hydraulic system as heretofore described. The pilot valve is provided with a vane 123 which divides the valve into two chambers. The position of the vane 123 is controlled by a pair of cams 124 which are adjustably mounted on a bar 125 carried by an arm 126 of the reciprocating sleeve 76 heretofore described and which is connected with the piston rod 91. These cams are arranged to engage and swing a lever 126 which is connected by a link 127 with an arm 128 of the vane.

The arrangement of the pilot valve mechanism is such that, when the parts are in the position shown in Fig. 5 (with the piston moving upward), the conduits 118 and 121 are in communication with each other, as are the conduits 117 and 122. Thus fluid pressure is applied to move the reversing valve control member 99 to the left (Fig. 5). When, however, the lower cam 124 strikes the lever 126 the vane will rotate, bringing the conduit 117 into communication with the conduit 121 and bringing the conduit 118 into communication with the conduit 122. This will cause the control member 99 of the reversing valve 85 to move to the right (Fig. 5) and reverse the direction of flow of fluid to and from the cylinder 89.

The number of passes that the workpieces make between the polishing rolls 12 and 14, is controlled by a valve 130 which is adjusted by a manually operable knob 23 heretofore mentioned as being mounted on the instrument panel 22. This valve is best illustrated diagrammatically in Fig. 5 and as there shown comprises a cylinder 131 having an inlet port 132 connected by a conduit 133 with the pressure line 84, and an exhaust port 134 which is connected by a conduit 135 with the exhaust conduit 98. A valve member in the form of a plug 136, having a peripheral groove 137 is rotatably mounted within the valve cylinder. Secured to this plug is a ratchet 138 and pivotally mounted about the axis of the plug is a lever 139 carrying a spring-pressed ratchet pawl 140, the ratchet pawl is moved in a step-by-step movement by the cams 124. As the lower cam 124 rises in response to the rising movement of the piston 90, it engages a lever 141 which is connected by a link 142 with the lever arm 139 which carries the ratchet pawl 140.

The arrangement of the ratchet advancing mechanism is such that the ratchet is advanced one tooth at the end of the upward stroke of the piston. A spring 143 acting on the lever 141 returns the ratchet pawl and the associated linkage to their normal positions. The usual detent pawl (not shown) is provided to maintain the ratchet wheel 138 in its advanced position. The gap or groove 137 in the plug 136 is arranged to bring the ports 132 and 134 of the valve structure in communication with each other, thus bringing the pressure line 84 into direct communication with the exhaust line 98, whereupon the movement of the piston 90 will cease due to a loss of pressure in the operating system heretofore described. Thus the number of passes of the wheel and work pieces is controlled by the angular position of a plug 136 of the valve 130.

When the workpieces are first inserted in the machine the operator grasps the knob 23 and moves it in a counterclockwise direction to a distance equal to that occupied by the number of ratchet teeth equivalent to the number of passes desired. For convenience, the instrument panel 22 is provided with a dial 23 A to enable the operator to manually move the plug to its starting position.

As heretofore described, synchronization of the peripheral speed of the rolls 12 and 14 is manually controlled by the actuation of the handwheels 26 and 27 which regulate the speed of the driven shafts of their respective speed reducer units. I have found that by placing an ammeter in the motor circuit of each of the roll driving motors, and by using substantially identical motors, the amperage reading indicated by each of these members is the same when the rolls are in synchronization. Thus, the operator may manipulate the handwheels 26 and 27 until the reading on the ammeters are identical, whereupon the peripheral speed of the rolls will be synchronized, thereby preventing undue abrasive wear on the rolls and eliminating the overloading of either motor.

The peripheral or surface speeds of the rolls 12 and 14 are synchronized while the driving motors are under load conditions, i. e., while the rolls are in working or peripheral contact with each other or the work. Under such conditions the load on the motors, which are identical, will be identical when the surface speeds of the rolls are identical. This is particularly true where the rolls are driven at relatively high speeds as is common in polishing machines. This manner of adjusting the surface or peripheral speeds of the rolls compensates for variations in the diameter of the rolls due to wear or the like.

The arrangement of the meters and the electrical circuit of the motors is best illustrated in the electrical diagram of Fig. 6. In this diagram the motor 15 is shown as being controlled by a relay 150, while the motor 16 is controlled by a relay 151. Both of these relays include a master switch mechanism 152, provided with contacts or switch members 153, 154 and 155, which are arranged, when closed, to connect their respective motors with power lines 156, 157 and 158. One of the switch members of each of the relays 150 and 151, namely, the switch member 154, is connected with a line 159 which leads to a transformer unit 160 of its respective ammeter 25, 24. The meters in turn are connected by lines 161 with the motors, thus placing the meters in series with their respective motors so that at all

times they indicate the operating condition of their respective motors.

The switch members 152 of the relays 150 and 151 are normally held in an open position by respective springs 162 and are closed by solenoids 163 and 164 respective. These solenoids, in turn, are controlled by a starter relay 187. When the apparatus is first placed in use, the operator depresses a starting switch 165 which completes a circuit from the power line 156 through a normally closed stop switch 166 and a normally closed testing switch 167 to the line 158, thus energizing a solenoid 169 and moving the switch arm 170 of the starter relay 187 against the action of its spring 172, thus closing the switch contact of its relay.

As soon as the relay 187 is energized, the starter switch may be released, whereupon the solenoid 169 will remain energized through a line 173 which bypasses the starter relay 187 and leads to a switch contact 174 and thence to the solenoid 169. Simultaneously with the closing of the switch arm 170, a switch contact 175 of the starter relay completes a circuit between the power line 156 and the solenoids 163 and 164, thus closing the relays 150 and 151. The switch contact 175 is connected to the power line 156 at a point between the stop switch 166 and the testing switch 167 by a line 176 and is connected by a line 177 with the solenoids 163 and 164, and they in turn are connected to the power line 158 by lines 178. Thus both relays 150 and 151 are energized thereby starting the operation of the roll mechanism.

To protect the ammeters 24 and 25, under the abnormally high starting load, the starting relay 187 is provided with a pair of switch members 180 and 181 which are connected by lines 182 and 183 respectively across the lines 159 and 161 of their respective ammeters, thus providing a shunt for the starting current and relieving the ammeters of the heavy starting load.

After the roll driving motor units 16 and 15 reach their normal driving operating speed, the operator depresses the button of the test switch 187, thereby opening the circuit to the line 173 and releasing the solenoid 169 and opening and starting relay 187. This places the ammeters in the circuit of the motors 15 and 16, which are held in operation by a switch member 184 of the relay 150. This switch member is connected by a line 185 with the power line 156 and by a line 186 with the solenoids 163 and 164, thereby holding both relays 150 and 151 closed despite the opening of the switch 175. This placing of the ammeters directly in the series with their respective motors provides a visible indication to the operator to enable him to adjust the speed reducer unit to synchronize the peripheral speed of the rollers 12 and 14.

When it is desired to stop the machine, it is only necessary to depress the stop switch 166, thus opening the power circuit 156, whereupon the relays 150 and 151 will both be released, permitting their springs to return them to an open position. A pressure switch is likewise provided to stop the operation of motor 100 should the fluid pressure driving the reciprocating mechanism at any time fail. This switch mechanism is best shown in Fig. 5 and comprises a pressure cylinder 190 which is in series with the pressure line 84 and is provided with a piston 191. The arrangement is such that should at any time the pressure in the line 84 drop below a predetermined amount, the spring indicated at 192 will open a switch 195 which is in series with the power line 156 leading to the

stop switch as shown in electrical diagram in Fig. 6.

An important advantage of the present invention is the fact that I have provided a method for indicating the relative peripheral speeds of the polishing rolls, and for quickly adjusting the speeds to maintain synchronization, regardless of the relative sizes of the rolls. Thus, the wear on the rolls is materially reduced and the degree of pressure desired on the work is readily controlled.

I claim:

1. A polishing apparatus comprising a polishing roll, a work holder mechanism, means for recurrently moving the work-holder toward and from the polishing roll to move a workpiece across the face of the roll, a fluid pressure system for actuating said mechanism, a control valve in said system, said valve being movable to release the fluid pressure to thereby interrupt the operation of the mechanism, means operable during the movement of said mechanism for intermittently advancing said control valve toward the releasing position, and means for adjusting the distance of movement for said control valve to become operative whereby the number of passes of the work across the face of the roll may be controlled.

2. A polishing apparatus comprising a pair of polishing rolls, a workholder mechanism for recurrently moving the workholder toward and from the bite of the polishing rolls to move a workpiece through the bite of said rolls, a fluid pressure system for actuating said mechanism, a control valve in said system, said valve being movable to release the fluid pressure thereby to interrupt the operation of said mechanism, means operable during the movement of said mechanism for intermittently advancing the control valve toward the releasing position, and means for controlling the flow of fluid in the system, whereby the rate of movement of the workpiece between the bite of the polishing rolls may be controlled.

3. A polishing apparatus comprising a polishing roll, a workholder mechanism for recurrently reciprocating the workholder toward and from the roll to move a workpiece across the face of the roll, a fluid pressure system for actuating said mechanism, said system including a hydraulic cylinder, a piston in said cylinder and connected to actuate said mechanism, a source of fluid pressure, a valve in said system to alternately connect each end of said cylinder with the source of fluid pressure and to exhaust the opposite end thereof, means controlled by the movement of said mechanism for actuating said valve, independent valves in said system for adjustably controlling the rate of flow of the exhausting fluid from each end of said cylinder to thereby independently control the rate of movement of the workholder in each of its reciprocating directions, and a pressure release valve in such system operable consequent upon a predetermined number of reciprocations of said mechanism to release the pressure supply in said system.

4. A polishing apparatus comprising a pair of coacting polishing rolls, a workholder mechanism for recurrently moving the workholder toward and from the bite of the polishing rolls to move a workpiece across the coacting faces of the rolls, a fluid pressure system for actuating said mechanism, a control valve in said system, said valve being movable to release the fluid pressure to thereby interrupt the operation of the mechanism, ratchet means operable by said mechanism for intermittently advancing said control valve toward the releasing position, and means for ad-

justing the distance of movement for said ratchet to become operative to move the valve to a releasing position, whereby the number of passes of the work across the face of the roll may be controlled.

5. A polishing apparatus comprising a pair of coacting polishing rolls, a workholder mechanism for recurrently reciprocating the workholder toward and from the bite of said rolls to move a workpiece across the coacting faces of the rolls, a fluid pressure system actuating said mechanism, including a hydraulic cylinder and piston, said piston being connected to actuate said mechanism, a source of fluid pressure, a valve in said system to alternatively connect each end of said cylinder with the pressure supply and exhaust the opposite end thereof, means controlled by the movement of said mechanism for actuating said valve, independent manually operable valves in said system for adjustably controlling the rate of flow of the exhausting fluid from the ends of said cylinder to thereby independently control the rate of movement of the workholder in each of its reciprocating directions, a pressure release valve in such system operable consequent upon a predetermined number of reciprocations of said mechanism to release the pressure supply in said system and means for manually determining the number of reciprocations to be made before the release valve becomes active.

6. A polishing apparatus comprising a pair of polishing rolls, an operating member, a workholder, a pair of parallel links pivotally interconnected between said member and said workholder, a fluid pressure system for moving the operating member to cause the movement of the workholder to and from the bite of said rolls to move a workpiece between the coacting faces of the rolls, independent motors for driving said rolls, means for swinging the parallel links about their pivotal connection with the operating member to move the workholder in a direction substantially parallel to the axes of the rolls, whereby a vibratory movement is imparted of the workholder in a direction transverse to the direction of reciprocation of the workholder, and an independent motor for actuating said last-named means.

7. In a polishing machine, a frame having a table, a pair of coacting polishing rolls suspended beneath the table with their axes in a substantially horizontal plane, a guide mounted on said table, a slide on said guide, a hydraulic ram connected to said slide to reciprocate the slide in a vertical direction on the column, a workholder connected to said slide whereby the reciprocation of the slide may pass the work between the bite of said rolls, means to align the rolls with the workholder, means to move the workholder in a direction substantially parallel with the axes of the rolls, a fluid pressure system for reciprocating said slide, said system including a pressure release valve, means actuated by the movement of said slide to move the release valve to a pressure releasing position consequent upon a predetermined number of passes of said work between the polishing rolls, and means in said system to control the rate of flow of fluid to thereby control the rate of speed of said reciprocating movement.

8. In a polishing machine, a frame having a table, a pair of coacting polishing rolls suspended beneath the table with their axes in a substantially horizontal plane, a vertically extending column mounted on said table, a slide on said column, a hydraulic ram connected to recipro-

cate the slide in a vertical direction on the column, a pair of links connected to said slide, a workholder pivotally connected to the lower ends of said links, whereby the reciprocation of the slide may pass the work between the bite of said rolls, means acting on one of said links to vibrate the workholder in a direction substantially parallel with the axes of the rolls, a fluid pressure system for reciprocating said slide and including a pressure release valve, mechanism actuated by the movement of said slide and coacting with said release valve to move the release valve to a pressure releasing position consequent upon a predetermined number of passes of said work between the polishing rolls, means in said system to control the flow of fluid to thereby control the rate of speed of such rolls of said reciprocating movement, and a pair of motors drivingly connected to respective rolls to drive the rolls.

9. In a polishing mechanism, a pair of polishing rolls, a workholder arranged and adapted to feed work into the bite of said polishing rolls, a constant speed electric motor for each roll, said motors being substantially identical electrically, a manually operable variable speed driving unit interposed between each motor and its respective roll, an electric circuit for controlling the operation of each of said motors, each circuit including an ammeter, a starting switch for initiating said circuits, means associated with said starting switch to cause said ammeters to be shunted out of the motor circuits, a second switch connected to release said shunt and render both ammeters active for causing both motors to cease to function in the event of failure of the electrical circuit for either motor.

10. The method of maintaining identical surface speeds of a pair of coacting polishing rolls of a polishing apparatus, each of which rolls is rotated by an independent electric motor, said motors being substantially identical and operated at substantially the same constant speeds comprising measuring the electrical load on each motor and varying the speed of the rolls to maintain substantially identical flow of current through the motors.

11. The method of maintaining identical surface speeds of a pair of coacting polishing rolls in a polishing machine each of which rolls is rotated by an independent electric motor which is connected to the rolls by a variable speed power transmission device, said motors being substantially identical and operated at substantially the same constant speeds comprising measuring the electrical load on each motor and varying the speed ratio of the power transmission device of one of the rolls until the current flow through both motors is identical.
